UNITED STATES PATENT OFFICE.

EDWARD C. SCHWAB, OF MILWAUKEE, WISCONSIN.

TRANSFER DEVICE FOR KNITTING-MACHINES.

1,294,839.

Specification of Letters Patent. Patented Feb. 18, 1919.

Application filed June 24, 1915. Serial No. 35,982.

To all whom it may concern:

Be it known that I, EDWARD C. SCHWAB, a citizen of the United States, and resident of Milwaukee, in the county of Milwaukee and State of Wisconsin, have invented new and useful Improvements in Transfer Devices for Knitting-Machines, of which the following is a description, reference being had to the accompanying drawings, which 10 are a part of this specification.

This invention relates to improvements in transfer devices for knitting machines.

In the knitting art it is the practice in varying the diameter of continuous knitted tubes or in varying the width of a knitted strip to terminate some of the lines of stitches or loops by transferring said stitches or loops to adjacent needles and continuing the knitting with a gradually lessening diameter or width until the desired reduction is obtained. This operation which heretofore has been done with manually actuated transfer needles and required considerable time and dexterity on the part of the operator, has been found to be impractical commercially on account of the skill, time and expense involved.

It is one of the objects of the present invention to overcome the before mentioned 30 objectionable features and provide a transfer device for knitting machines which will be automatically operated mechanically at the same speed as and in conjunction with the knitting machine.

35 A further object of the invention is to provide a transfer device for knitting machines in which the device will automatically drop lines of stitches and tie the terminating end of stitch to the next adjacent stitch line.

40 A further object of the invention is to provide a transfer device for knitting machines which is of simple construction and which may be easily mounted upon an ordinary knitting machine.

45 A further object of the invention is to provide a transfer device for knitting machines which while primarily adapted to be actuated automatically by suitable mechanism, may, if desired, be operated by hand. While 50 the present application illustrates and describes a means for automatically operating the parts, the invention will be confined more particularly to the transfer device itself as the said device may be actuated in 55 many different ways.

With the above and other objects in view, the invention consists of the improved transfer device for knitting machines and its parts and combinations as set forth in the claims and all equivalents thereof. 60

In the accompanying drawings in which the same reference characters indicate the same parts in all of the views:

Figure 1 is a transverse sectional view of the improved transfer device for knitting 65 machines taken on line 1—2 of Fig. 4;

Fig. 2 is a similar view taken on the same line with the parts in a different position;

Fig. 3 is a longitudinal sectional view thereof taken on line 3—4 of Fig. 1, a portion 70 of the knitted fabric being shown;

Fig. 4 is a similar view thereof taken on the same line with the parts in a different position and showing the manner of transferring the terminating loop of a stitch line 75 to one of the loops of an adjacent stitch line;

Fig. 5 is a sectional detail view taken on line 5—5 of Fig. 1;

Fig. 6 is a sectional view taken on line 6—6 of Fig. 1; 80

Fig. 7 is an enlarged detail view of the transfer device and one of the knitting needles; and

Fig. 8 is a side detail view of a spring beard needle. 85

Referring to the drawings the numeral 8 indicates a portion of a knitting machine 90 indicates a portion of a knitting machine bed of ordinary form and which is provided with transverse needle grooves 9 to receive knitting needles 10 reciprocally mounted therein. The needles are held in place by a gib bar 11 and are formed with upstanding bent heel portions 12 which project out of the grooves and above the bed. These bent heel portions are engaged by the cam lock 95 (not shown) of the machine to reciprocate the needles in an ordinary manner well known to the art.

The needles illustrated are of the kind commonly termed "latch-needles", being provided with hook-like portions 13 on their forward ends and with hinged guard latches 14 which close the open side of the hook when swung forwardly. These latches serve to permit the loops of yarn on the shanks to 105 slide off the hooked ends of the needles, thus engaging the loops with new loops which have been previously formed in the hooked portions of the needles in the ordinary manner. The transfer device is also adapted for 110

use in connection with what is known as spring beard needles.

The gib bar 11 also forms a guide for a 5 slidable frame 15 upon which is mounted the improved transfer device about to be described. This frame is of angular form and is provided with rearwardly extending rectangular guide arms 16 and a forwardly extending guide plate 17 positioned on a 10 higher elevation than the guide portion. A transversely reciprocal member 18 slidably mounted between the side arms 16 is provided with a forwardly projecting portion 19 terminating at its forward end in an L-shaped guide portion 20 slidably supported by the guide plate 17. This reciprocal member 18 is moved back and forth by a cam 21 which engages an arm 22 extending rearward from said member. One-half portion 25 21' of the cam is concentric with the axis of the cam so that during one-half revolution of the cam the member 18 remains in its forward position.

The depending part of the portion 20 25 carries a slidable transfer guard member 23 which extends downwardly and is provided with an eyed angular bent portion 24 through the elongated eye 25 of which the transfer needle 26 passes. The transfer needle 26 consists of a length of wire having a hook-like lower end portion 27 with a downwardly extending point or end 28. The lower part of the hook is grooved as indicated by the numeral 29, Fig. 7, to receive the upper edge portions of the knitting needles 10 engaged by the transfer needle and the point 28 enters the small groove 28' formed in the knitting needles to permit the yarn to pass over said point 30 to the hook portion. The shank portion of the transfer needle is formed with a coil 26' to provide for the yielding engagement of the lower end of the needle with the knitting needles, and the upper end of the shank extends into a needle opening provided in the guard and is held in position by a bolt 30 and reciprocates with the guard forwardly and rearwardly. The guard and the transfer needle are also reciprocated 35 vertically by means of levers 31 and 32 which are medially, pivotally mounted on portions of the reciprocal member 18, and controlled by a cam 33 which engages the lever 32. In order to reciprocate the parts 40 vertically while they are moving forwardly and rearwardly, the lever 32 is of the telescoping type and its rear part 34 which is engaged by the cam is slidably connected to a fixed arm 35 projecting rearwardly 45 from the frame 17. This arm 35 is provided with a slot 36 into which a bolt 37 extends thus holding the lever part 34 in engagement with the cam 33 during the reciprocatory movements of the member 18. 50 The forward end of the lever 32 has a pin

and slotted engagement 38 with the rear end of the lever 31 so the levers can swing in their respective arcs.

The transversely reciprocal member 18 is provided with a needle guide groove 39 in its lower side to receive the upstanding heel portions 12 of the knitting needles so that the needles thus engaged will be reciprocated back and forth by said member during the knitting operation. The entrance or 75 mouth 40 of the groove 39 is of flaring form to guide the needle heels into the groove 39.

The reciprocal member 18 is divided into three parts of which the movement of the upper part 41 is controlled by the cam 21 and the two lower parts 42 and 43 are moved by a cam 44 which engages an arm 42' projecting rearwardly from the lower member 42. Each lower part 42 and 43 has pivotally connected thereto and extending forwardly therefrom link members 45 and 46 which are pivotally connected at their forward ends to the opposite ends of a lever 47 fulcrumed on the forward portion 15' of the slidable frame 15. The construction 90 and arrangements of parts provides for the lower part 43 being pushed rearwardly when the part 42 is pushed forwardly by the cam 44 so that the knitting needles engaged by said part 43 will be moved to a 95 position to be deflected out of working position by the beveled edge 43' of the part 42.

The forward edge portion of the knitting machine bed 8 is provided with upwardly projecting shoulders or bits 8' which form 100 the feed line of the yarn and hold the knitted fabric 48 in position.

The loop of the material to be transferred is indicated by the numeral 49 and the loop of the material over which it is to be passed 105 is indicated by the numeral 50.

The retrieving springs for the respective parts are indicated by the numerals 51, 52 and 53.

The cams of course travel with the frame 110 15 so that the parts engaged by said cams remain in engagement therewith.

In operation the knitting needles are reciprocated back and forth in the usual manner to form the fabric and when it is desired to narrow the fabric by dropping lines of stitches the transfer needle which is normally above and free from contact with the knitting needles is moved to the needle, the loop of which is to be transferred and the 115 transfer needle is moved downwardly into engagement with the shank of the needle with the lower side portions of the transfer needle extending on opposite sides of the shank of the knitting needle engaged, when 120 the knitting needle is in its rearward position and its guard latch being in open position. The loop 49 of the yarn which is 125 in the knitting needle hook is received by the hooked end of the transfer needle on a 130

forward movement of both transfer and knitting needles, and the knitting needle is then reciprocated rearwardly out of loop 49. The slideable transfer frame is now moved laterally over the knitting needles the distance of one needle so that the loop 49 of the material is swung over at an angle into register with and in front of the next adjacent knitting needle and as this needle is 5 in turn reciprocated forwardly it will pass through the transferred loop. While the knitting needle is in this position the transfer needle is moved downwardly by the cam 33 and the retrieving spring 51 into engagement with the knitting needle and the transferred loop 49 slips out of the hooked end of said transfer needle into the hook portion of the knitting needle as the said knitting needle and the transfer needle are 10 moved rearwardly. The transfer needle is then raised away from the needles and the frame 15 is moved to one end of the needle bed, out of action until such time as another narrowing of the goods is desired. 15 On the next normal knitting operation, the new yarn which is received by the knitting needle will be drawn through the two loops now in the hook of the needle and they will be firmly attached. The modified form 20 shown in Fig. 8 indicates the use of the transfer device with a spring bearded needle. 25 While this application describes in a general way a means for operating the transfer device, it is to be understood that other means may be employed for accomplishing the same result without departing from the spirit and scope of the invention, and it is also to be understood that this application relates more particularly to the transfer device 30 itself rather than to the means for operating it. Also while the action is described with reference to a single knitting needle, in practice the loops from four or more needles are transferred the distance of 35 one needle simultaneously.

What I claim as my invention is:

1. A transfer device for a knitting machine having a plurality of knitting needles, comprising a transfer needle extending above and at an angle to the knitting needles and operable to engage one of the needles and having a hooked end portion which takes the terminating yarn loop therefrom and transfers it to the next adjacent needle 50 and then moves away from this last mentioned needle.

2. A transfer device for a knitting machine having a plurality of knitting needles, comprising a transfer needle extending above and at an angle to the knitting needles and operable to engage one of the needles and having a hooked end portion which takes the yarn loop therefrom, said transfer needle also being successively operable to 55 engage one of the knitting needles until the

yarn loop is passed therefrom to the said transfer needle, then raised while the knitting needle passes out of the loop, then moved laterally until it is opposite the next adjacent needle, then movable into engagement with said second needle and in a position to transfer the loop to said second needle, and finally movable away from said needle after the needle has been transferred. 70

3. A transfer device for a knitting machine having a plurality of knitting needles, comprising a transfer needle extending above and at an angle to the knitting needles and having a hook portion on one end, and means for imparting to the said transfer 75 needle a cycle of movements in which the said needle engages the shank of one of the knitting needles and takes the yarn loop from said needle when the needle is moved forwardly, then being moved laterally to 80 the next adjacent needle while said next needle is in its rearward position positions the yarn loop so that as the second needle is moved forwardly it will pass through and receive said loop on a rearward movement 85 of both transfer and knitting needle.

4. A transfer device for a knitting machine, consisting of a shank portion formed with a loop and having a hook provided with a down-turned point, the outer peripheral edge portion of the hook only being provided with a needle groove. 95

5. A transfer device for a knitting machine, consisting of a shank portion having a curved part formed adjacent to one of its 100 ends, a portion of the curved part being provided with a needle groove extending only along its curved length.

6. A transfer device for a knitting machine, consisting of a shank portion formed 105 with a loop and having a curved portion hook provided with a down-curved point, the outer peripheral edge portion of the hook being only provided with a needle spine. 110

7. A transfer device for a knitting machine, having a plurality of knitting needles, comprising a transfer needle member extending above and at an angle to the knitting needles and having a grooved hooked 115 portion operable to engage one of the knitting needles and take the terminating yarn loop therefrom on a forward movement of said knitting needle and transfer it to the next adjacent knitting needle on a return 120 or rearward movement of said adjacent knitting needle.

8. A transfer device for a knitting machine, having a plurality of knitting needles, comprising a transfer needle extending 125 above and at an angle to the knitting needles and having a grooved hooked portion, said transfer needle being operable to be positively positioned in intimate relation with one of said knitting needles, said transfer 130

needle also being movable to the next adjacent knitting needle, and means for holding and positioning said transfer needle to allow the said adjacent needle to positively and freely pass through the transferred yarn loop on a forward movement and to receive said yarn loop from said transfer needle on its rearward movement.

9. A transfer device for a knitting machine, having a plurality of knitting needles, comprising a transfer needle member extending above and at an angle to the knit-

ting needles and having a grooved hooked portion operable to receive a yarn loop from and while in intimate engagement with one 15 of said knitting needles on its forward movement, to carry said yarn loop laterally in front of the next adjacent knitting needle and to deposit said yarn loop into the hook of said next adjacent needle on its 20 rearward movement.

In testimony whereof, I affix my signature.

EDWARD C. SCHWAB.
